UNITED STATES PATENT OFFICE

1,997,540

SLICING MACHINE

William J. Campbell, Indianapolis, Ind., assignor
to American Slicing Machine Company, Chi-
cago, Ill., a corporation of New York

Application November 2, 1932, Serial No. 640,785

2 Claims. (Cl. 146—102)

My invention relates to an improvement in slicing machines and has for one purpose the provision of a slicing machine which shall be light, small, and easy to handle but which shall have the efficiency, speed and capacity of considerably larger machines. Another object is the provision of improved guiding means for a pusher plate for a slicing machine. Other objects will appear from time to time in the course of 10 the specification and claims.

The present application contains material divided out of application 598,131, filed on March 11, 1932, and issued as Patent 1,961,959.

I illustrate my invention more or less diagrammatically in the accompanying drawings, wherein—

Figure 1 is a top plan view with parts in horizontal section;

Figure 2 is a front elevation; and

Figure 3 is an end elevation.

Like parts are indicated by like symbols throughout the specification and drawings.

Referring to the drawings, A generally indicates any suitable base having anti-vibrational pads or supports A¹ which rest upon any suitable supporting surface A² for example a counter or the like.

B indicates a motor housing mounted on the base A. B¹ is the motor shaft and B² a pulley on the shaft about which passes a belt B³.

C indicates a housing extension projecting upwardly from the base A. Formed integrally with it is a flared sleeve C¹ terminating rearwardly in a generally cylindrical portion C². Positioned within the portion C², the details of which form no part of the present invention and are not indicated herein, is any suitable bearing means for the knife shaft C³ on which is mounted a pulley C⁴ and the knife C⁵. As will be seen for example in Figure 1 the pulley is positioned within and is housed by the member C¹ but the cutting edge of the knife C⁵ extends outwardly beyond it as at C⁶, the rear face of the knife being notched or recessed as at C⁷ to receive and overlap the outer edge of the member C¹. Any suitable means may be employed to hold knife and pulley in place, for example the axial screw C⁸ and the radially spaced screws C⁹. The knife may be removed from the

knife shaft, while leaving the pulley in place, by removing the screw C⁸. The pulley may be removed by loosening the screws C¹⁰. C¹¹ indicates an end wall of the upward housing projection C and C¹³ the rear wall. As is shown in Figure 1, the rear wall is apertured as at C¹⁴ to per-

mit the passage therethrough of the motor shaft B¹ and of a portion of the motor housing B.

The forward face of the upstanding housing member C is closed by the guard plate generally indicated as E, the details of which do not of themselves form part of the present invention.

Positioned on the base and forwardly of the knife are the tracks H, H¹, the outer track H¹ being for example mounted on outwardly extending arms H². Both tracks are preferably cylindrical. Movable along said tracks is a carriage member generally indicated as H³ which

includes one or more track engaging members or sleeves H⁴ engaging the inner track H. I herein illustrate two longitudinally separated sleeves H⁴ but it will be understood that a single sleeve might be employed, preferably of considerable extension. The carriage also includes or is provided with a roller supporting bracket H⁵ in

which is pivoted a roller H⁶. The roller may be mounted on a pin H⁷ preferably fixed, upon which pin it may be axially movable. Preferably the roller H⁶ is positioned intermediate the sleeves H⁴, the position in which it is shown for example in Figure 2. Mounted on the carriage H³ is the work receiving member which includes a main portion H⁸ downwardly inclined forwardly toward the knife when the parts are in the position shown in Figure 2. At the lower

edge is an angle H⁹ at right angles thereto and with a rounded upper edge portion H¹⁰. The portion of the member H⁸ adjacent the cutting plane extends outwardly as at H¹¹ to terminate in the rolled edge H¹². The outer portion terminates as at H¹³. H¹⁴ indicates a guide pin mounted on the carriage.

J indicates a pusher plate having the handle J¹ and forward work engaging pins or points J². Extending rearwardly from the handle is the arm J³ which terminates in a sleeve J⁴ adapted to ride on the pin or guide H¹⁴. It will be understood that the arm J³ is of sufficient length to clear the portion H¹¹ of the work receiving member H⁸. The handle J¹ is provided with an upwardly extending rib J⁵, as illustrated in Figures 1 and 2. J⁶ indicates a fiber washer secured to the lower edge of the pusher plate J, and in slidable relationship with the work receiving member H⁸.

M indicates any suitable gauge plate the details of which do not of themselves form any part of the present invention. It will be understood that the gauge plate may be actuated as by the control member M¹.

N indicates any suitable slice receiving member at the rear of the knife.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

The structure herein described and shown forms a light, easily operated and efficient slicing machine of the manual feed type, in which the rotary knife C⁵ is rotated at relatively high speed by electric motor means. The carriage H³ is guided by the tracks H, H¹, but the carriage is moved manually by the hand of the operator. Mounted on the carriage for movement along a path preferably at right angles to the cutting plane is the pusher plate J, which is also manually operated. For example, the operator may grasp with his hand the sleeve J⁴, the arm J³ or the handle J¹. By thrusting forwardly along the cutting plane and somewhat inwardly toward the cutting plane the work is thrust into effective contact with the forward face of the gauge plate M. A continuation of the inclined thrust carries the carriage and the work, properly gauged, against the cutting edge of the knife C⁵. The slice is cut and falls upon the slice receiving tray N. The work meanwhile continues across the face of the guard plate E until the work has been entirely carried past the cutting edge and the slice has been severed. The operator then manually withdraws the carriage and repeats his inclined thrust for the ensuing stroke and slice.

The operator, in employing the pusher plate, may grasp the sleeve portion of the member J³. He may then put his forefinger on top of the portion J⁴, the rib J⁵ being between his first and second fingers. His remaining fingers, being free of the pusher plate structure may grasp the sleeve portion J³. The operator may thereby hold the pusher plate firmly downwardly against the work support H⁸, preventing any tendency it might have to kick up especially on the return stroke.

It will be noted that the carriage is mounted upon the two tracks H, H¹, two sleeves H⁴ slidably engaging the track H and a roller engaging the outer track H¹. This roller H⁶, sliding as well as rotating on the pin H⁷, may conform readily to any slight variation in the distance separating the two tracks. This prevents any cramping or noise resulting from any slight misalignment of the tracks and makes a precise positioning of the two tracks less important, which is a help in manufacture and assembly. Note also that the circumferential groove of the roller H⁶ is of different cross-sectional shape than the opposed face of the track H¹. It may be arcuate but if so should be of an arc of less diameter. In other words, I prefer to have the roller engage the track at two laterally spaced points rather than have it engage the track over an extended area. I find that when there is a thoroughly conforming engagement over a substantial area, foreign material if any tends to pack and the operation becomes more noisy.

I claim:

1. In a slicing machine, a base, a knife thereon and means for actuating it, a carriage, and means for guiding the carriage past the cutting edge of the knife, said guiding means including a plurality of spaced tracks, bearing sleeve means, associated with the carriage, engaging one of said tracks, and a roller, mounted on the carriage, engaging the other of said tracks, said roller being provided with a circumferential track engaging groove having an arcuate transverse profile of lesser diameter than that of the opposed portion of the track, said roller engaging said track at a plurality of laterally spaced points. 30

2. In a slicing machine, a base, a knife thereon and means for actuating it, a carriage, and means for guiding the carriage past the cutting edge of the knife, said guiding means including a plurality of spaced cylindrical tracks, bearing sleeve means, associated with the carriage, engaging one of said tracks, and a roller, mounted on the carriage, engaging the other of said tracks, said roller being provided with a circumferential track engaging groove having an arcuate transverse profile of lesser diameter than that of the opposed portion of the track, said roller being free for axial movement. 40

WILLIAM J. CAMPBELL. 50
